N. S. Vedder & Ezra Ripley, of Troy, N. Y.
Assignors to Potter & Co. of same place.
Letters Patent No. 1185. Dated Jan³ 1860.

The schedule referred to in these Letters Patent and making part of the same.

To all whom it may concern:

Be it known that we, N. S. Vedder & Ezra Ripley, each of the City of Troy, in the County of Rensselaer, and State of New York, have invented or produced a new and original Design for the side-plates of a Troy Stove; and we do hereby declare that the following is a full and exact description of the same, reference being had to the annexed photographic drawing, making a part of this Specification.

Our said design consists of the stock and scroll-leaves, a, a' berry-like rosette, b, scrolls c, c', scroll-leaves d, d', and e, e', bells f, f', and borders g, g', all formed and arranged together into a large symmetrical ornament and displayed upon a double-checked or scale-work ground h, as shown in the annexed photograph.

What we claim as our joint invention or production and desire to secure by Letters Patent, is, the ornamental design herein described and represented in the annexed photographic drawing, for a stove plate, or plates.
